DESIGN FOR A CUP DISPENSING CABINET

Samuel N. Hope, Wauwatosa, Wis., assignor to Lily-Tulip Cup Corporation, New York, N. Y., a corporation of Delaware

Application July 22, 1940, Serial No. 93,832

Term of patent 3½ years

To all whom it may concern:

Be it known that I, Samuel N. Hope, a citizen of the United States residing at Wauwatosa, in the county of Milwaukee and State of Wisconsin, have invented a new, original, and ornamental Design for Cup Dispensing Cabinets, of which the following is a specification, reference being had to the accompanying drawing, forming part thereof.

In the drawing,

Fig. 1 is a front elevation of a cup dispensing cabinet, showing my new design;

Fig. 2 is a side elevation;

Fig. 3 is a rear elevation, and

Fig. 4 is a top view.

I claim:

The ornamental design for a cup dispensing cabinet, substantially as shown.

SAMUEL N. HOPE.
